UNITED STATES PATENT OFFICE.

JOHN W. DUNCAN AND JOHN A. SHUTE, OF GREENWOOD, MISSISSIPPI.

MATTRESS ATTACHMENT.

1,312,110.

Specification of Letters Patent.

Patented Aug. 5, 1919.

Application filed May 24, 1919. Serial No. 299,459.

To all whom it may concern:

Be it known that we, JOHN W. DUNCAN, a citizen of the United States, residing in Greenwood, in the county of Leflore and 5 State of Mississippi, and JOHN A. SHUTE, a citizen of the United States, residing in Greenwood aforesaid, have invented certain new and useful Improvements in Mattress Attachments, of which the following is a 10 specification.

This invention has for its principal object to provide a mattress with an attachment, which may be used to protect the feet of the occupant of a bed from drafts of cold air 15 when arranged at the foot of the bed, or to protect the head of the occupant when arranged at the head of the bed.

Another object of the invention is to provide an attachment of the kind referred to, 20 which may be permanently attached to the mattress, but in such way that when set in an upright position to serve as a protector on an occupied bed, it will be securely held there and when lowered to a horizontal position 25 on an unoccupied bed, it will be held in place with the fastening devices concealed.

A further object of the invention is to so construct such an attachment that it may be 30 easily applied to or removed from a bed when desired.

In carrying out our invention, we provide what we call a pad of such size that it extends entirely across the bed, and of such 35 height that it will prevent drafts of air from striking the feet of the occupant. The pad is provided with straps or their equivalent, which are attached to the foot end of the mattress and to the pad about midway 40 between its upper and lower ends, by which arrangement the pad, while in upright position, is held firmly against the foot frame of the bed, and when lowered to a horizontal position on the mattress, the straps will 45 be entirely concealed.

In the accompanying drawings:—

Figure 1 is a perspective view of a mattress with our improvements applied, showing by dotted lines the outlines of the bed 50 frame.

Fig. 2 is a view on an enlarged scale and in section showing how the pad is lowered onto the mattress and how the straps which connect the pad to the mattress are con- 55 cealed.

Fig. 3 is a perspective view of a modification in which the straps which attach the pad to the mattress, instead of being attached to the upper edge of the pad, are connected directly to the middle portion thereof. 60

We have shown our improvements applied to a mattress A and bed frame B of usual construction. The pad M at the foot of the bed may be made of any suitable material such as ticking stuffed with cotton, and the 65 ticking may be covered with a more ornamental or attractive material if desired. Short straps N, having buckles n, are permanently secured to the foot of the mattress, preferably being attached directly to a reinforcing strip N' extending from side 70 to side of the mattress, as shown. Straps O, extending along the rear side of the pad from top to bottom thereof, are attached at o to the upper edge of the pad and extend 75 through loops y formed in a strap P attached to the middle portion of the rear side of the pad at x.

When the pad is in use as shown in Fig. 1, it is held by the straps O closely against the 80 foot frame of the bed, but when it is desired to lower the pad as when the bed is unoccupied, it may be done by taking hold of the 85 lower part of the pad and drawing it toward the head-board so that the pad will move to the position shown by dotted lines with the straps entirely concealed.

If desired a similar pad may be used at the head of the bed as indicated in Fig. 1 and employed as a head protector or as a bolster 90 or sham pillow.

If desired, the pad may be quickly removed from the bed by loosening the straps from the buckles in an obvious way.

While we prefer to connect the straps O to 95 the upper edge of the pad and extend them through loops in a strap extending across the middle portion of the pad as shown in Fig. 1, we may connect the upper ends of the straps to the strap P as indicated in Fig. 100

3. In either case the straps are connected with the pad at the middle portion thereof in such manner that when the pad is in upright position the straps so hold it that it will not readily move from this position, 105 inasmuch as it is drawn against the foot frame of the bed and furthermore, when the pad is moved to a horizontal position in an unoccupied bed it may be readily done without withdrawing the pad from the foot por- 110

- tion of the bed and in such manner as to entirely conceal the straps. The mattress may be reversed if desired and the pads operated as before explained.
5. Inasmuch as the pad at the head of the bed is attached to the mattress in precisely the same way as the pad at the foot of the bed further description of the invention is unnecessary.
10. It will be observed that the straps O are connected with the middle portion of the rear side of the pad so that the pad may be readily moved to the position shown by dotted lines in Fig. 1 and as also shown in Fig. 2. This could not be done if the straps were connected to the lower edge or end of the pad.
- We claim as our invention:
1. The combination with a mattress, of a protecting pad provided with fastening devices connected with the rear or outer side of the pad near the middle portion thereof between its upper and lower ends and connected also with the adjacent end of the mattress.
  2. The combination with a mattress, of a protecting pad provided with straps connected with the rear or outer side of the pad near the middle portion thereof between its upper and lower ends and detachably connected with the adjacent end of the mattress.

3. The combination with a mattress, of a protecting pad provided with straps attached to the pad at its upper edge, and connected with the pad near the middle portion thereof, and means for attaching the free ends of the strap to the mattress.

4. The combination with a mattress, of a protecting pad, a strap extending across the rear portion of the pad from one side thereof to the other, straps attached to the upper edge of the pad and extending through loops in said first mentioned strap, and means for connecting said vertically arranged straps to the adjacent end of a mattress.

5. The combination with a mattress, of a protecting pad provided with a strap extending horizontally across its rear portion midway between its upper and lower ends, and from side to side on the pad, means for forming loops in the strap, vertically arranged straps attached to the upper edge of said pad and extending through said loops, straps attached to the adjacent end of the mattress, and fastening devices for connecting said last mentioned straps to the vertically arranged straps.

In testimony whereof, we have hereunto subscribed our names.

JOHN W. DUNCAN.

JOHN A. SHUTE.
